UNITED STATES PATENT OFFICE.

CARL P. NACHOD, OF PHILADELPHIA, PENNSYLVANIA, ASSIGNOR TO NACHOD SIGNAL COMPANY, INC., A CORPORATION OF NEW YORK.

SIGNALING SYSTEM.

1,225,736.

Specification of Letters Patent.

Patented May 8, 1917.

Application filed September 18, 1914. Serial No. 862,264.

To all whom it may concern:

Be it known that I, CARL P. NACHOD, a citizen of the United States, residing in the city of Philadelphia, county of Philadelphia, and State of Pennsylvania, have invented a new and useful Signaling System, of which the following is a specification.

My invention relates to electrical signaling systems for controlling traffic on rail-
ways, and more particularly electric rail-
ways.

My invention relates more particularly to such a system in which all the signals are light signals, though it will be understood that disk, semaphore or blade signals, or other types of signals may be used either in place of or with some or all of the light signals.

In my preferred arrangement, though my invention is not limited thereto, I employ a clear signal (preferably green) for indicating that a track or block is clear; a danger or stop signal (preferably red) and with the latter two alternating signals (preferably yellow) which with the red or stop signal gives a permissive signal or indication, the yellow signals alternating for such successive car or train entering a track section or block.

My invention resides in the system and apparatus of the character hereinafter described.

For an illustration of one of various forms my invention may take reference is to be had to the accompanying drawings, in which:

Figure 1 is a front elevation of a signal box showing one arrangement of light signals.

Fig. 2 is a diagrammatic view of one of my arrangements of circuits and apparatus embodying my invention.

Fig. 3 is a side elevational view, partly in section, showing switching mechanism which may be used in the system shown in Fig. 2.

Fig. 4 is a horizontal sectional view taken on the line A—A of Fig. 3.

Fig. 5 is a sectional view, some parts in elevation, taken on the line C—C of Fig. 3.

Fig. 6 is a horizontal sectional view, some parts in plan, taken on the line E—E of Fig. 5.

Fig. 7 is a vertical sectional view, some

parts in elevation, taken on the line D—D of Fig. 4.

55

Fig. 8 is a sectional view, parts in elevation, taken on the line B—B of Fig. 3.

Fig. 9 is an end elevational view of another form of alternating switch.

Referring to Fig. 1, a signal box 6 is shown to have four signal windows or lenses, which may themselves be colored and behind which within the box are disposed the signal lights, such as electric incandescent lights. The upper signal may be 65 the clear or green signal G, the next below the red or stop signal R, and the lower yellow lights or signals Y, Y1 staggered to either side of the signal R.

In the system about to be described, it 70 will be assumed that the green light G is displayed when the track or block is clear; that the red light R is a danger or stop signal indicating, when displayed alone, that the track or block ahead is occupied; and 75 that a permissive indication or signal is given when the red light R and either of the yellow lights Y or Y1 are simultaneously displayed; and that when such a permissive signal is displayed, as R and Y si- 80 multaneously, the entry of another vehicle or train into the track section or block will cause extinction of the light Y and the display of the light Y1, so that R and Y1 are displayed, still giving a permissive indica- 85 tion or signal, but indicating to the motor-man or driver of said vehicle or train that such vehicle or train has counted in or affected the signaling circuits or apparatus.

Referring now to Fig. 2, 1 represents the 90 trolley wire or other contact conductor of an electric railway system, a track or block section extending between the turn-outs 2 and 2' at stations A and B, the normal directions of vehicle or train movements be- 95 ing indicated by the arrows.

Similar apparatus is illustrated at both stations A and B, the parts at station B corresponding with similar parts at station A being designated by similar reference characters with the addition of prime marks.

At or near each end of the block, that is, at each turn-out, there is directionally sensitive vehicle controlled contact mechanism which may be of any suitable type, such as 105 electro-magnetic, as illustrated, for example,

at 11, 18 in my prior Patent No. 1,108,927, or simply mechanical as here elementally illustrated. In electrical connection with the contact conductor 1 are the movable contacts 3, 4, 3', 4' which may be deflected in either direction to engage the co-operating stationary contacts 5, 6, 5', 6'.

The contacts 5, 5 are electrically connected together and to the conductor 7 which connects with one terminal of the electro-magnet or solenoid S, which may be termed the signal setting magnet, whose other terminal is connected with the earth E or other return conductor of the electric railway system. The contacts 6, 6 are connected to each other and to the conductor 8 which connects with one terminal of the electro-magnet or solenoid C, which may be termed the signal clearing magnet, whose other terminal connects with the earth or return conductor E.

One terminal of the electro-magnet H is permanently connected by conductor 9 with the contact or feed conductor 1, while its other terminal is connected to the stationary switch contact 10 normally in electrical communication with the stationary switch contact 11 through the movable switch contact 12. The contact 11 is connected with the conductor 13 which extends from station A to station B where it connects with the contact 11' communicating through movable switch contact 12' with the switch contact 10' connecting with one terminal of the electro-magnet H' whose other terminal connects with the earth or return conductor E. It is apparent, therefore, that under normal conditions, as illustrated in Fig. 2, the electro-magnets H and H' are in series with each other and normally energized and therefore hold their armatures 14 and 14' in their attracted positions indicated against the contacts 15 and 15', whereby current normally flows from the conductor 1 through conductors 9, 9', armatures 14, 14', contacts 15, 15' and the green or clear signal lights G and G' to earth or return conductor E, causing their display and indication at both stations that the block is clear. It will be noted that the magnets H, H' which hold the signals at clear, are both energized from one end of the block through a conductor extending along the block between stations.

Associated with the armature 14 of magnet H is a contact 16 connected to one terminal of the red signal light R whose other terminal is connected to the earth or return conductor E. Thus when the magnets H and H' are de-energized their armatures drop and cause energization of the red lights R and R'.

And a contact 17 is adapted to be engaged by armature 14 when magnet H is de-energized, such contact 17 being connected to stationary switch contact 18 normally in electric connection with the switch contact

19 through the movable switch contact 20. The contact 19 is connected with a contact 21 of the clearing magnet C, the contact 21 normally engaging the stationary contact 22 which connects with a conductor 23 extending from station A to station B where it connects with the contact 21' movable with the armature of the clearing magnet C', the contact 21' normally engaging the stationary contact 22' connected with the switch contact 19' normally connected with switch contact 18' through the movable switch contact 20', the contact 18' being connected with the contact 17' adapted to be engaged by the armature 14' of magnet H'. 80

Connected with the contact 19 and contact 21 is a contact 24 adapted to be connected to contact 25 by the movable switch contact 26, the contact 25 being connected through conductor 27 with one terminal of the electro-magnet D whose other terminal connects to the earth or return conductor E. The armature 28 of the electro-magnet D is connected by conductor 29 with one terminal of the electro-magnet C and also with the stationary switch contact 30 normally in communication with the switch contact 31 through the movable switch contact 32, the contact 31 being connected with conductor 33 which extends between the stations 95 and thence through switch contacts 31', 32', 30' with the conductor 29'. The armature 28, when attracted, is adapted to engage contact 34 connected with conductor 33. Movable with the armature 28 of electro-magnet 100 D is the movable switch contact 35, connected with conductor 9, and adapted, when the armature 28 is attracted, to engage the stationary contact 36 which is connected with the contact 37 bearing upon the rotatable 105 conducting member 38 having the staggered contacts 39 and 40 on opposite sides. The stationary brushes or contacts 41 and 42, adapted to engage the contacts 39 and 40, respectively, are connected respectively to terminals of the yellow lamps Y and Y1 whose other terminals connect with the earth or return conductor E. 110

The switch contacts 12, 20, 26 and 32 may be attached to a common movable member, 115 as in the switching mechanism more particularly hereinafter described, and are controlled by magnets S and C.

The solenoids S and C are shown in Figs. 3 and 5. Each has a movable core 43, 120 whose attraction is opposed by a spring 44, a rod 45 being connected with the core 43 and carrying a member 46 upon which is pivoted at 47 the dog or pawl 48 adapted to engage the ratchet or toothed wheel 49 to 125 step the same around one notch each time the core 43 is attracted. Or any equivalent arrangement may be used in which the wheel 49 is stepped around by the action of the solenoid. In Fig. 3 the toothed wheel 130

for the solenoid S is indicated at 50, its actuating dog or pawl at 51 and the member to which the latter is pivoted is indicated at 52.

In the brackets 53, 53, Fig. 4, is secured 5 the non-rotatable shaft 54 upon which the ratchet or toothed wheels 49 and 50 are rotatable. The ratchet wheel 49 is secured to the driving clutch member 55 between whose sections are movable longitudinally 10 of the shaft 54 the driven clutch member 56 secured to or a part of the cam member 57, (see Figs. 3, 5 and 7), a spring 58 holding the cam member 57 toward the right in the position shown in Fig. 4, and 15 opposing the movement of said cam member 57 toward the left. Embracing the circular rib 59 on the cam member 57 are the strap members 60, 60 secured to each other by the screws 61. Pivoted to the 20 members 60, 60 by screws 62, 62 is the member 63 in the form of a jaw upon the upper end of the rod 64, the latter pivoted at 65 in brackets 66, suitable lost motion being allowed at one or the other 25 of the pivotal connections to allow the rod 64 to swing to the right and left as viewed in Fig. 3 without binding or locking. At the lower end of the rod 64 is provided a plate or extension 67 to which is secured 30 by screws 68, 68 a plate 69 of insulating material to which are secured the movable switch contacts 12, 20, 26 and 32 coöperating with the stationary contacts supported by the stationary insulating member 70.

35 Disposed beside the cam member 57, and rotatable upon the shaft 54, is the disk or member 71 secured to the ratchet or notched wheel 50 of solenoid S. A pivot pin or screw 72 pivots the roller 73 to a flattened portion of the periphery of member 71, the 40 roller 73 normally engaging in the cam surface or depression 74 in the member 57, which latter has a lug 75 while the member 71 has a corresponding lug 76, the 45 lugs 75 and 76 adapted to engage each other to limit the relative rotation of members 57 and 71 with respect to each other.

Rotatable in fixed relation with the ratchet wheel 50, actuated by the signal 50 setting solenoid S, is the alternating switch for the yellow lights Y, Y1. This switch comprises the metallic disk or wheel 38 insulated from and secured by screws 77 to the flange 78 rotatable with the wheel 50. Extending to one side of disk 38 are the contact lugs 39 being staggered with respect to lugs 40, the contact 37 being in 55 electrical communication with all the contact lugs all the time, while brushes or contacts 41 and 42 engage respectively and alternately the contact lugs 39 and 40, so that as the wheel 50 is rotated electrical connection is made through brush 37 first with brush 41, then with brush 42, and then 60 with brush 41, and so on alternately.

As shown in Figs. 3 and 8, these brushes are supported upon the insulating member 79.

Or the alternating switch for the permissive signal lights may take the form shown 70 in Fig. 9 where the contact 37 is stationary and held by or constituting a part of the bracket 80 secured to the base 81 of insulating material. Upon this base of insulating material the contacts 41 and 42 are 75 supported respectively on the ends of the levers 82 and 83 pivoted to the base 81, a spring 84, insulated from one or both of said levers, being normally under tension to draw said levers toward each other. On 80 these levers are pivoted the rollers 85, 86 adapted to engage the star wheel 87 driven by the ratchet wheel 50. As the star wheel rotates it withdraws one of the movable contacts from engagement with the stationary contact 37 and allows the spring to bring the other into engagement with the stationary contact, these movable contacts alternately engaging the stationary contact, 85 there being a change for each step of movement of the ratchet wheel 50.

When the solenoids C and S are energized 90 they move their ratchet wheels 49 and 50 one notch, thereby rotating the members 57 and 71 a like distance in the direction 95 indicated by the arrows in Fig. 3. The parts are normally in the position indicated in Fig. 3. If, however, the solenoid S only is energized the member 71 only will be stepped forward and this will cause 100 the roller 73 to thrust against and ride up upon the cam surface 74 of member 57 until the roller 73 bears upon the lateral face of the disk or member 57. This movement causes a longitudinal movement of the 105 member 57 with respect to the shaft 54, this movement being in opposition to spring 58 and carries the member 60 toward the left, as viewed in Fig. 3, which accordingly 110 tilts the lever 64 about its pivot 65 in a counter-clockwise direction, causing the switch to move from the position indicated in Fig. 3 to the position in which the contact 26 engages the contact 25. If, now, the solenoid C is energized and steps member 115 57 around, but not as many steps as the member 71 has been stepped, the switch will remain in the position last described, namely, with contact 26 in engagement with contact 25. If, however, the number of 120 energizations of solenoid C should become equal to the number of energizations of the solenoid S, the member 57 will have overtaken the member 71 and will have returned to the relative position indicated in Fig. 125 3, under influence of spring 58, because the cam notch 74 will have come opposite the roller 73. This return movement causes the separation of contact 26 from contact 25 and shifts the bar 64 and the switch 130

back to the normal position indicated in Fig. 3.

By this construction the switch is shifted only upon an excess of energizations of one of the solenoids over the number of energizations of the other. The switch is shifted only upon an excess movement of one of the ratchets over the other and is independent of the actual angular position of the two ratchets or the two members 57 and 71. And by the construction above described the magnets or solenoids S and C are enabled to make their strokes or movements simultaneously and independently or dissimultaneously.

And after a predetermined excess movement by one of the ratchet wheels, the lugs 75 and 76 will engage and prevent further relative movement between members 57 and 71. That is, should such a number of cars or trains occupy the block at the same time that the lugs 75 and 76 have been brought into engagement with each other, further cars or trains entering the block will produce no effect because the member 71 will carry with it the member 57, member 71 having made substantially a complete revolution. Were this positive drive of member 57 by member 71 not afforded, such further cars or trains entering the block would cause, at a certain stage, the improper clearing of the signals. With the parts in normal position as indicated in Figs. 3 and 4, the lug 75 is about to engage lug 76, and should the solenoid C be energized before solenoid S lug 75 would engage lug 76 and cause member 71 to follow member 57, thereby maintaining the switch in its normal position indicated in Fig. 3.

The operation of the system is as follows: When there is no car or train in the block, the green lights G and G' will be displayed at both stations because the magnets H and H' are normally energized as previously described.

A car or train arriving at one end of the block will be advised by the display of the green light that the block is clear and that it may enter. Upon entering the block as from station A, that is, from left to right, Fig. 2, the car or train will actuate the contact member 3 to engage the contact 5, whereupon the solenoid or electro-magnet S at station A will be temporarily energized, thus stepping around the ratchet wheel 50 one notch and causing the shifting of the switch by rod 64 as previously described, from its normal position, indicated in Figs. 2 and 3, to the position where contact 26 bridges contacts 24 and 25, and contacts 12, 20, and 32 separate from their co-operating stationary contacts. The result is that contact 12, having separated from contacts 10 and 11, breaks the circuit through the magnets H, H' whose arm-

tures 14, 14' are then no longer attracted and drop and engage the lower contacts 16, 17 and 16', 17'. This causes rupture of current through the green signals G and G' and establishment of current through the red signals R and R'. At station B only the red signal R' will be displayed, while at station A the red signal R and a yellow signal Y will be displayed, the red signal R being controlled by the release of armature 14, as described, and the yellow light signal Y being displayed because movable switch contact 26 is now in engagement with stationary contacts 24 and 25 which causes electro-magnet D at station A to be energized by current flowing from station B from conductor 1 through conductor 9' to armature 14', contact 17', to contact 18', through contact 20' to contact 19' through contacts 22', 21', conductor 23, contacts 22 and 21, contacts 24, 26 and 25 through the winding of the electro-magnet D and thence to earth or return conductor E. When the electro-magnet D is energized it attracts its armature 28 which carries with it the movable contact 35 which now engages contact 36, whereupon current flows from the conductor 1 at station A through conductor 9, contacts 35 and 36, brush 37, thence through a contact 39 which is now in engagement with brush 41 through the yellow signal Y to earth or return conductor E. It will accordingly be seen that upon entry of the first car or train into the block the clear or green signal will be discontinued, a red danger or stop signal will be displayed at the opposite end of the block, and at the home end of the block a red and yellow permissive signal will be displayed indicating that the block is occupied and further indicating that other cars or trains may enter the block from the same end, the red and yellow signals simultaneously displayed constituting the permissive signal or indication.

If, now, another vehicle or train enters the block from the same end, the electro-magnet or solenoid S will be again energized and will step its ratchet wheel 50 around another notch, but as hereinbefore explained the switch will remain in its abnormal position because the roller 73 is bearing upon the lateral face of the member 57, thus holding the switch in such abnormal position. But in making this further step, the ratchet wheel 50 has carried around the alternating switch so as to cause a contact 39 to separate from brush 41, thus extinguishing yellow light Y, and bringing a contact 40 into engagement with brush 42, thereby displaying yellow light Y1. To the driver of the second train or car this change will be visible, because, as seen in Fig. 1, the left hand yellow light Y will be extinguished, and the right hand

- light will glow, showing the motorman of the second car or train that his car or train has counted in, that is, has caused the step movement of the apparatus described. And 5 a third car or train proceeding toward the same entrance of the block will thus receive a permissive signal and may enter, and upon entering will cause all signals to remain the same as before except that the 10 signal Y1 will be discontinued and signal Y will again be displayed. And so on, a series of cars or trains may enter the block in the same direction, each alternating the yellow signals.
- 15 And when a car or train leaves the block at station B the contact 3' will be caused temporarily to engage the contact 6' whereupon magnet C' at station B will be energized as will also the magnet C at station A, the latter receiving its current from station 20 B through contacts 3' and 6' through conductor 8', conductor 29', contacts 30', 32' and 31', conductor 33, and now through contact 34 to armature 28 of magnet D, which, 25 it will be remembered, has previously been energized upon entry of a car or train to the left end of the block, thence to conductor 29 through the winding of electro-magnet C to earth or return conductor E. Upon energization of magnet or solenoid C the ratchet 30 wheel 49 will be stepped around one notch as will the member 57, so that member 57 gains one step upon member 71. And each car leaving the block at station B will cause 35 energization of magnet C as described. And when as many cars or trains shall have left the block as entered it, member 57 will have overtaken member 71 and cam notch 74 will have been brought opposite roller 73 allowing 40 restoration of the switch to the normal position indicated in Figs. 2 and 3, whereupon the magnets H, H' are again energized, the green lights again displayed, and the red and yellow lights extinguished.
- 45 As stated, upon departure of each train or vehicle from the block at station B the electro-magnet C' at station B is energized. But such energization, has no effect, and is incidental only, because in the mechanism 50 at station B the lug 75 will engage the lug 76 and cause the member 71 to be moved around with the member 57, these members therefore maintaining their normal position with respect to each other, and preventing 55 shifting of the switch at station B from its normal position shown in Fig. 2.
- If a car enters the block, as from the left, and then backs out again at the same station A, solenoid S is first energized through 60 contacts 3 and 5, and then solenoid C is energized through contacts 4 and 6, or 3 and 6, the result being, irrespective of whether there is a car or train on the block, that the effect of entry is immediately canceled, be- 65 cause the step forward of the car counting
- or step-by-step mechanism caused by solenoid S is immediately overtaken or canceled by the step forward caused by the solenoid C.
- Suppose a car or train has entered the 70 block from left to right at station A, a permissive indication, red and yellow, will be displayed at station A and a red or stop signal will be displayed at station B as previously described. If, now, with the car or train in the block, a car or train should wrongfully enter the block from station B against this red or stop signal displayed at station B, the solenoid S' at station B will be energized because of engagement of contact 5' by contact 4' or because of engagement of contact 5' by contact 3', depending upon the track at station B from which the car or train wrongfully enters the block. Such energization of solenoid S' will cause 75 the switch at station B to move from normal to abnormal position, thus separating contact 20' from contacts 18' and 19', and thereby breaking the circuit through conductor 23 and electro-magnet D at station 80 A, thus causing extinction of the yellow light at station A, with a red stop signal light only remaining at station A. When the car or train which has so wrongfully entered the block against the red light at 85 station B backs out again at station B to either of the tracks, the solenoid C' at station B will be energized either through contacts 3', 6' or contacts 4', 6'; and since contact 32' has been separated from contacts 30' and 31' the solenoid C at station A cannot be energized simultaneously with the last mentioned energization of solenoid C' at station B. And should the car or train come to rest in such position that either contacts 90 3', 6' or 4', 6' remain in engagement, the continued energization of solenoid C' having restored the switch at station B to normal, will nevertheless hold contacts 21' and 22' separated, thus preventing current flowing from conductor 1 at station B through conductor 9', armature 14', contact 17', conductor 23 and winding of magnet D at station A. And the prevention of energization 95 of magnet D prevents a display of a yellow light at station A, thus maintaining only a red light or stop signal at station A, and the prevention of energization of magnet D, when solenoid C' remains energized at station B prevents closure of circuit between 100 armature 28 and contact 34 and therefore prevents energization of magnet C at station A: In other words, even should the car or train backing out from the block at station B remain on the contactor, that is, keep 105 the circuit through the vehicle-controlled contact and solenoid C' closed, solenoid C' only will be energized and the solenoid C at station A will not be energized.
- If now the car should move off of the 110

115 120 125 130

5 contactor out of the block, that is, cause de-energization of the solenoid C', contacts 21' and 22' will be reengaged, and the electro-
magnet D at station A will be again ener-
gized, causing display of a yellow light with
the red light at A and closing contacts 34
and 28 preparatory to further energization
of magnet C when the car or train on the
block leaves the block at station B.

10 While the signals are herein shown as
energized from the conductors furnishing
the electric power to the electric railway
system, the voltage of such power system
often fluctuating widely in practice, it will
15 be understood that the signals may be ener-
gized by current from a separate constant
potential source, in which case, when the
signals are lights, they will not fluctuate
widely in brilliancy with fluctuations of the
20 voltage on the power circuit.

25 And the circuit arrangements herein de-
scribed are such that if the voltage on the
power circuit should fail, and assuming the
signals to be operated by current from a
separate source as above referred to, only
30 red light signals could be displayed, be-
cause with failure of voltage upon the
power circuit the magnets H, H' would
drop their armatures and close the circuits
of the red lights only.

35 It will be noted that the green and yel-
low lights are displayed only when the
magnets H, H' and D, D' are energized.
Accordingly, any accident that would cause
40 failure of magnetism in the magnets H, H',
as failure of voltage upon the power cir-
cuit, open circuiting or short circuiting of
the magnet windings, or breaking of the
signal conductor 13, could only cause a
45 change from any previous signal indication
to a stop indication, that is, could only
cause energization of the red lights; and
any failure of the magnets D, D', or fail-
ure of their current supply, would cause
50 extinction of the yellow lights, leaving
only the red stop signals. The armatures
of the magnets H, H' form two-position
switches, each in one position causing ener-
gization of the green light and in the other
55 position the energization of the red light,
the structure being such that it is impossi-
ble to have both the green and the red
lights displayed simultaneously.

60 And it will be noted that the yellow
lights are controlled from the distant end
of the block, thus constituting an answer-
back or indication from the red signal at
the distant end of the block, and any fail-
ure of the armature of the magnet, as H',
65 to drop and set a red signal, would with-
hold the yellow light at the home end of
the block.

65 Pursuant to a requirement for division
switching mechanism of the character illus-
trated in Figs. 3 to 9 inclusive is claimed

in divisional application Serial Number
159,397, filed April 3, 1917.

What I claim is:

1. In a signaling system for vehicles,
plural aspect signaling means comprising
70 three signal elements, means including a
vehicle controlled switch for displaying
one only of said signal elements alone, and
means for displaying said one of said sig-
nal elements with either one of the other
75 signal elements.

2. In a signaling system for vehicles,
plural aspect signaling means comprising
80 three signal elements, means including a
vehicle controlled switch for displaying
one only of said signal elements alone, the
display of said one of said signal elements
giving a stop indication, and means for
displaying said one of said signal elements
85 with either one of the other of said signal
elements to form a permissive signal.

3. In a signaling system, plural aspect
signaling means comprising three signal
elements, means for displaying one only of
90 said signal elements alone, the display of
said one of said signal elements giving a
stop indication, means for displaying said
one of said signal elements with another of
95 said signal elements to form a permissive
signal, and means for displaying said one
of said signal elements with the remaining
one of said signal elements to likewise give
a permissive signal, the change from the
display of signal elements which give one
100 permissive signal to that of signaling ele-
ments which give another permissive signal
giving a third indication.

4. In a signaling system for vehicles, a
stop signal, a plurality of similar signal
elements associated with said stop signal,
105 and means including a vehicle controlled
switch for displaying said signals, each of
said signal elements when displayed with
said stop signal forming a permissive sig-
nal, one of said similar signal elements
110 being disposed to one side of said stop sig-
nal and at a height different from said
stop signal.

5. In a signaling system for vehicles, a
stop signal, a plurality of similar signal
elements associated with said stop signal,
115 and means including a vehicle controlled
switch for displaying said signals, each of
said signal elements when displayed with
said stop signal forming a permissive sig-
nal, said stop signal being disposed above
120 said similar signal elements, one of said
signal elements being disposed to one side
of said stop signal.

6. In a signaling system for vehicles,
125 clear and stop signals disposed one verti-
cally above the other, a plurality of simi-
lar signal elements associated with said
stop signal, and means including a vehicle
controlled switch for displaying said sig-
130

nals, each of said signal elements when displayed with said stop signal forming a permissive signal.

7. In a signaling system for vehicles, clear and stop signals disposed one vertically above the other, a plurality of similar signal elements associated with said stop signal, and means including a vehicle controlled switch for displaying said signals, each of 5 said signal elements when displayed with said stop signal forming a permissive signal, said similar signal elements being disposed at the same height and at a height different from said stop signal.
15. 8. In a signaling system for vehicles, clear and stop signals disposed one vertically above the other, a plurality of similar signal elements associated with said stop signal, and means including a vehicle controlled switch for displaying said signals, each of 20 said signal elements when displayed with said stop signal forming a permissive signal, said similar signal elements being disposed at the same height and at a height different from said stop signal, and one of 25 said similar signal elements being disposed at one side of said stop signal.

9. In a signaling system for vehicles, a stop signal, a plurality of similar signal elements associated with said stop signal, and means including a vehicle controlled switch for displaying said signals, each of 30 said signal elements when displayed with said stop signal forming a permissive signal, said signal elements being disposed at the same height and at a height different from that of said stop signal.

10. In a signaling system, a block section, an electro-magnet at each end of said block, a signal controlled by each of said electro-magnets, a signal conductor connecting said electro-magnets at all times in series with each other, whereby they are energized or deenergized simultaneously, said electro-magnets normally energized from one end of said block, said signals being displayed in response to deenergization of said electro-magnets, a switch in said signal conductor at each end of said block, and 45 vehicle controlled means at each end of said block for controlling both of said switches.

11. In a signaling system, a block section, an electro-magnet at each end of said block, a signal controlled by each of said electro-magnets, a signal conductor connecting said electro-magnets in series with each other, said electro-magnets being normally energized from one end of said block, said signals being displayed in response to deenergization of 55 said electro-magnets, a normally closed switch in said signal conductor at each end of said block, and means at each end of said block responsive to vehicle movement for controlling both of 60 said switches.

12. In a signaling system, a block section, an electro-magnet at each end of said block, a signal controlled by each of said electro-magnets, a signal conductor connecting said electro-magnets in series with each other, said electro-magnets being normally energized from one end of said block, said signals being displayed in response to deenergization of said electro-magnets, a normally closed switch in said signal conductor at each end of said block responsive to movement of a vehicle into said block for opening said switch at that end of the block and simultaneously deenergizing said magnets, so and means responsive to departure of the vehicle from said block for re-closing said switch.

13. In a signaling system, a block section, an electro-magnet at each end of said block, a signal conductor connecting said electro-magnets at all times in series with each other whereby they are energized or deenergized simultaneously, said electro-magnets being normally energized from one end of said block, a signal controlled by each of said electro-magnets, and means responsive to simultaneous deenergization of said electro-magnets for discontinuing display of said signals, and vehicle controlled means at each end of said block for controlling both of 90 said switches.

14. In a signaling system, a block section, an electro-magnet at each end of said block, a signal conductor connecting said electro-magnets at all times in series with each other whereby they are energized or deenergized simultaneously, said electro-magnets normally energized through said conductor from one end of said block, clear and stop signals at each end of said block, and means responsive to deenergization of the electro-magnet at each end of said block for discontinuing display of said clear signal and displaying said stop signal, and vehicle 100 controlled means at each end of said block for controlling both of said switches.

15. In a signaling system, a block section, an electro-magnet at each end of said block, a signal conductor connecting said electro-magnets at all times in series with each other, said electro-magnets being normally energized from one end of said block, a signal controlled by each of said electro-magnets, means responsive to deenergization 115 of each of said electro-magnets for discontinuing display of said signal, a normally closed switch in said signal conductor at each end of said block, and means at each end of said block responsive to vehicle 120 movements into and out of said block for opening and closing said switch at that end of the block, and simultaneously deenergizing and energizing said magnets.

16. In a signaling system, a block section, 125

an electro-magnet at each end of said block, a signal conductor connecting said electro-magnets at all times in series with each other, said electro-magnets normally energized through said conductor from one end of said block, clear and stop signals at each end of said block, means responsive to de-energization of the electro-magnet at each end of said block for discontinuing display 5 of said clear signal and displaying said stop signal, a normally closed switch in said signal conductor at each end of said block, and means at each end of said block responsive to vehicle movements into and out of said 10 block for opening and closing said switch at that end of the block and simultaneously deenergizing and energizing said magnets.

17. In a signaling system, a block section, a stop signal at each end of said block, 20 a second signal associated with the stop signal at one end of said block to form therewith a permissive signal, means responsive to the entry of a vehicle into said block at said one end thereof for displaying the stop signal at the other end of said block and for displaying the stop signal and said second signal at said one end of said block.

18. In a signaling system, a block section, a stop signal at each end of said block, a 30 plurality of similar signals at one end of said block associated with the stop signal thereat, each of said similar signals when displayed with said stop signal forming a permissive signal, means responsive to the 35 entry of a vehicle into said block at said one end thereof for displaying the stop signals at both ends thereof and for displaying one of said similar signals with the stop signal at said one end of said block, and means 40 responsive to the entry of subsequent vehicles into said block for alternating said similar signals.

19. In a signaling system, a block section, a stop signal at each end of said block, a 45 normally energized electro-magnet at each end of said block preventing display of said stop signal, a second signal associated at the home end of the block with the stop signal thereat and adapted to be displayed there- 50 with to form a permissive signal, means re- 55 sponsive to the entry of a vehicle into said block at the home end for displaying the stop signals at both ends of said block, a signal conductor controlling said second signal, display of said second signal at the home end of said block being controlled 60 through said conductor upon de-energization of said electro-magnet at the distant end of said block.

60 20. In a signaling system, a block section, a stop signal at each end of said block, a normally energized electro-magnet at each end of said block preventing display of said stop signal, a second signal associated with 65 each stop signal and adapted to be displayed

therewith to form a permissive signal, means responsive to the entry of a vehicle into said block at the home end for displaying the stop signals at both ends of said block, a signal conductor controlling said second signals, display of said second signal at the home end of said block being controlled through said conductor upon de-energization of said electro-magnet at the distant end of said block, a normally open switch in said signal conductor at each end of said block, said switch at the home end of said block being closed upon entry of said vehicle into said block, and the switch at the distant end of said block remaining open, whereby a 70 75 80 permissive signal is displayed at the home end of said block and only a stop signal at the distant end of said block.

21. In a signaling system, a block section, a stop signal at each end of said block, a normally energized electro-magnet at each end of said block preventing display of said stop signal, a second signal associated with each stop signal and adapted to be displayed therewith to form a permissive signal, means 90 responsive to the entry of a vehicle into said block at the home end displaying the stop signals at both ends of said block, a signal conductor controlling said second signal, display of said second signal at the 95 home end of said block being controlled through said conductor upon de-energization of said electro-magnet at the distant end of said block, a third signal similar to said second signal, and means responsive to entry 100 of successive vehicles into said block for alternating said second and third signals.

22. In a signaling system, a block section, a stop signal at each end of said block, a normally energized electro-magnet at each 105 end of said block preventing display of said stop signal, a second signal associated with each stop signal and adapted to be displayed therewith to form a permissive signal, means responsive to the entry of a vehicle into said block at the home end for displaying the stop signals at both ends of said block, a signal conductor controlling said second signals, display of said second signal at the home end of said block being controlled through said conductor upon de-energization of said electro-magnet at the 110 distant end of said block, a normally open switch in said signal conductor at each end of said block, said switch at the home end of said block being closed upon entry of said vehicle into said block, the switch at the distant end of said block remaining open, whereby a permissive signal is displayed at the home end of said block and only a stop signal at the distant end of said block, a third signal similar to said second signal, and means responsive to entry of successive vehicles into said block for alternating said second and third signals.

23. In a signaling system, a block section, a stop signal at each end of said block, a plurality of similar signals each adapted to coöperate with a stop signal to form a 5 permissive signal, means responsive to the entry of a vehicle into a block at one end thereof for displaying the stop signals at both ends thereof, said similar signals at said one end of said block being controlled 10 from the distant end of said block.

24. In a signaling system, a block section, a stop signal at each end of said block, a plurality of similar signals each adapted to coöperate with a stop signal to form a per- 15missive signal, means responsive to the entry of a vehicle into a block at one end thereof for displaying the stop signals at both ends thereof, said similar signals at said one end of said block being controlled from the dis- 20tant end of said block, and means responsive to entry of successive vehicles into said block for alternating said similar signals.

25. In a signaling system, a block section, a signal at each end of said block, a signal 25 conductor, a switch in said conductor at each station, a signal setting magnet controlling said switch, a signal clearing magnet at each station, a second signal conductor connecting said clearing magnets in 30 parallel with each other, a pair of switches at each station in parallel with each other in said second signal conductor, one of said switches operated with said first named switch, a third electro-magnet at each sta- 35tion controlling the other of said pair of switches, and a switch closed when said first named switch is opened controlling said electro-magnet.

26. In a signaling system, a block section, 40 a signal at each end of said block, a signal conductor, a switch in said conductor at each station, a signal setting magnet controlling said switch, a signal clearing magnet at each station, a second signal conductor connecting said clearing magnets in 45 parallel with each other, a pair of switches at each station in parallel with each other in said second signal conductor, one of said switches operated with said first named switch, a third electro-magnet at each sta- 50tion controlling the other of said pair of switches, and a switch closed when said first named switch is opened controlling said electro-magnet, a second signal at each end 55 of said block coöperating with said first named signal to form a permissive signal, said third electro-magnet controlling said second signal.

27. In a signaling system, a block section, 60 a signal at each end of said block, a signal conductor, a switch in said conductor at each station, a signal setting magnet controlling said switch, a signal clearing magnet at each station, a second signal conductor connecting said clearing magnets in

parallel with each other, a pair of switches at each station in parallel with each other in said second signal conductor, one of said switches operated with said first named switch, a third electro-magnet at each sta- 70tion controlling the other of said pair of switches, a switch closed when said first named switch is opened controlling said electro-magnet, a plurality of similar signals at each end of said block controlled by 75 said third electro-magnet, and means for alternating said similar signals, each of said similar signals when displayed with said first named signal forming a permissive signal. 80

28. In a signaling system, a block section, a signal and an electro-magnet controlling the same at each end of the block, a switch controlling said magnets to simultaneously energize and deenergize the same, independ- 85ently and simultaneously operable step-by-step mechanisms at each end of the block section, signal setting electro-magnets controlling one of said step by step mechanisms at each end respectively of the block sec- 90tion, signal clearing magnets operating another of said step-by-step mechanisms at each end respectively of the block section, and means at each end of the block section responsive to excess movement of one of said 95 step-by-step mechanisms for controlling said switches respectively.

29. In a signaling system, a block section, a signal at each end thereof, a switch controlling each of said signals, independently 100 and simultaneously operable step-by-step mechanisms, a signal setting electro-magnet controlling one of said step-by-step mechanisms, a signal clearing magnet operating another of said step-by-step mechanisms, 105 means responsive to excess movement of one of said step-by-step mechanisms for controlling said switch, and means for causing the step-by-step mechanism normally actuated by the signal setting magnet to be actuated independently thereof when said clearing magnet is the first to operate after said step-by-step mechanisms are in normal position. 110

30. In a signaling system, a block section, 115 a signal at each end thereof, a switch controlling each of said signals, independently and simultaneously operable step-by-step mechanisms, a signal setting electro-magnet controlling one of said step-by-step mecha- 120nisms, a signal clearing magnet operating another of said step-by-step mechanisms, means responsive to excess movement of one of said step-by-step mechanisms for controlling said switch, and means operative 125 after predetermined excess movement of said step-by-step mechanism controlled by said signal setting magnet for carrying with it the step-by-step mechanism normally actuated by said clearing magnet. 130

31. In a signaling system, a block section, a signal at each end thereof, a switch controlling each of said signals, independently and simultaneously operable step-by-step mechanisms, a signal setting electro-magnet controlling one of said step-by-step mechanisms, a signal clearing magnet operating another of said step-by-step mechanisms, means responsive to excess movement of one of said step-by-step mechanisms for controlling said switch, means operative after predetermined excess movement of said step-by-step mechanism controlled by said signal setting magnet for carrying with it the step-by-step mechanism normally actuated by said clearing magnet, a plurality of similar signals associated with each of said signals, and a switch for alternating said similar signals actuated by said step-by-step mechanism controlled by said signal setting magnet.

32. In a signaling system, a block section, a stop signal at each end of the block, a second signal associated with each stop signal to form therewith a permissive signal, means responsive to the entry of a vehicle into said block at either end thereof for displaying the stop signal at the other end of said block and for displaying the stop signal and said second signal at the entering end of said block.

33. In a signaling system, a block section, a stop signal, a plurality of similar signal elements associated with said stop signal, each of said signal elements when displayed with said stop signal forming a permissive signal, and means responsive to the entry of a vehicle into said block for setting the stop signal and displaying therewith one of said similar signal elements.

34. In a signaling system, a block section, a stop signal, a plurality of similar signal elements associated with said stop signal, each of said signal elements when displayed with said stop signal forming a permissive signal, means responsive to the entry of a vehicle into said block for setting the stop signal and displaying therewith one of said similar signal elements, and means responsive to the entry of another vehicle into said block for alternating said similar signal elements.

35. In a signaling system, a block section, a stop signal, a plurality of similar signal elements associated with said stop signal, each of said signal elements when displayed with a stop signal forming a permissive signal, a vehicle controlled switch, a step-by-step mechanism controlled by said switch to display said stop signal and one of said similar signal elements upon entry of a vehicle into said block, and a switch for alternating said similar signal elements driven with said step-by-step mechanism.

36. In a signaling system, a block section,

a stop signal at each end of said block, a plurality of similar signals associated with a stop signal, each of said similar signals when displayed with said stop signal forming a permissive signal, means responsive to the entry of a vehicle into said block at either end thereof for displaying the stop signals at both ends thereof and for displaying one of said similar signals with the stop signals at the entering end of said block, and means responsive to the entry of subsequent vehicles into said block for alternating similar signals.

37. In a signaling system, a signal, signaling means associated therewith, vehicle controlled means for displaying said signal alone to produce one signal indication and to display said signaling means with said signal to produce a different signal indication, vehicle counting mechanism, and means controlled thereby for changing the aspect of said signaling means when displayed with said signal, whereby said different signal indication persists but the aspect thereof changes.

38. In a signaling system, a stop signal, a plurality of similar signal elements associated with said stop signal, each of said signal elements when displayed with said stop signal forming a permissive signal, a signal setting magnet, a signal clearing magnet, step-by-step mechanisms actuated by said signal setting and clearing magnets, means responsive to excess movement of one of said step-by-step mechanisms for controlling said signal and said signal elements, and means for alternating said similar signal elements actuated with the step-by-step mechanism controlled by said signal setting magnet.

39. In a signaling system, a stop signal, a plurality of similar signal elements associated with said stop signal, each of said signal elements when displayed with a stop signal forming a permissive signal, vehicle counting mechanism, a vehicle controlled magnet controlling said mechanism, and means for alternating said similar signal elements controlled by said vehicle controlled magnet.

40. In a signaling system for vehicles, plural aspect signaling means comprising three signal elements, two of which are similar to each other and dissimilar to the remaining one, means for displaying alone said dissimilar element only, and means including a vehicle controlled switch for displaying either of said similar elements with said dissimilar element.

41. In a signaling system for vehicles, plural aspect signaling means comprising three signal elements, two of which are similar to each other and dissimilar to the remaining one, means including a vehicle controlled switch for displaying alone said dissimilar signal element only, the display

of said dissimilar signal element giving a desired indication, and means for displaying said dissimilar signal element with either one of said similar signal elements to form a 5 permissive signal.

42. In a signaling system, plural aspect signaling means comprising three signal elements, two of which are similar to each other but dissimilar to the remaining one, 10 means for displaying alone said dissimilar element, the display of said dissimilar element giving a stop indication, means for displaying one of said similar elements with said dissimilar element for forming a permissive signal, and means for displaying the 15 other of said similar elements with said dissimilar element for likewise forming a permissive signal, the change from the display of said dissimilar element with one of said 20 similar elements to that of the dissimilar element with the other of said similar elements giving a different indication.

43. In a signaling system for vehicles, plural aspect signaling means comprising a 25 plurality of signal elements all but one of which are similar to each other and dissimilar to the one, means including a vehicle controlled switch for displaying alone the dissimilar element only, and means for displaying each of said similar elements singly with said dissimilar element.

44. In a signaling system for vehicles, plural aspect signaling means comprising a 30 plurality of signal elements all but one of which are similar to each other and dissimilar to the one, means including a vehicle controlled switch for displaying alone the dissimilar element only, the display of said dissimilar element giving a stop indication, and means for displaying each of said 35 similar elements singly with said dissimilar element to form permissive indications.

45. In a signaling system for vehicles, plural aspect signaling means comprising a plurality of signal elements all but one of 45 which are similar to each other and dissimilar to the one, means including a vehicle controlled switch for displaying alone the dissimilar element only, and means for displaying with said dissimilar element less 50 than the whole number of similar elements.

46. In a signaling system for vehicles, plural aspect signaling means comprising a plurality of signal elements part of which are similar to each other but dissimilar to 55 the remaining ones, said remaining ones being dissimilar to each other, means including a vehicle controlled switch for displaying alone the dissimilar elements only, and means for displaying with less than the 60 whole number of dissimilar elements less than the whole number of similar elements.

47. In a signaling system for vehicles, plural aspect signaling means comprising a 65 plurality of stationary signal elements all but one of which are similar to each other and dissimilar to the one, and means for displaying alone said dissimilar element only and for displaying with said dissimilar element certain of said similar elements, 70 including a switch operated upon the passage of vehicles, each operation of said switch when one of said similar signal elements is displayed causing a change of said last mentioned signal element to non-display condition and the display of another of 75 said similar signal elements.

In testimony whereof I have hereunto affixed my signature in the presence of the two subscribing witnesses.

CARL P. NACHOD.

JOSEPH W. STONE.

Copies of this patent may be obtained for five cents each, by addressing the "Commissioner of Patents, Washington, D. C."

It is hereby certified that in Letters Patent No. 1,225,736, granted May 8, 1917, upon the application of Carl P. Nachod, of Philadelphia, Pennsylvania, for an improvement in "Signaling Systems," errors appear in the printed specification requiring correction as follows: Page 1, line 28, for the word "such" read *each*; page 9, line 83, claim 28, after the word "switch" insert the words *at each end of the block section*; and that the said Letters Patent should be read with these corrections therein that the same may conform to the record of the case in the Patent Office.

Signed and sealed this 26th day of June, A. D., 1917.

[SEAL.]

R. F. WHITEHEAD,
Acting Commissioner of Patents.

Cl. 246—36.
